UNITED STATES PATENT OFFICE.

ADOLF WASCHNACK, OF NEU FINKENKRUG, GERMANY, ASSIGNOR TO SIEMENS & HALSKE AKTIENGESELLSCHAFT, WERNERWERK, OF SIEMENSSTADT, NEAR BERLIN, GERMANY.

TELEPHONE SYSTEM.

Application filed March 1, 1924, Serial No. 696,180, and in Germany March 29, 1923.

The invention relates to automatic telephone systems and more particularly to a circuit arrangement for switches having movement in one direction and having several groups of contacts, over which subscriber's lines can be reached by one or more trains of impulses.

The invention consists in that over certain contact groups connections are set up with lines leading to subscriber's lines and over other groups with lines leading to succeeding connecting devices which may be operated in any manner desired, and after the wipers have been set by number impulses on a line leading to a succeeding connecting device, the switching means, e. g. side switch, of the switch is so influenced that switching operations are prevented, which take place when a subscriber's line is taken into use, for example ringing, and that the positioning devices of the switch are withdrawn from the influence of further number impulses transmitted by the calling party.

The drawings comprising Figs. 1, 2 and 3 show diagrammatically by way of example one embodiment of the invention.

In Fig. 1, a substation T_n , a finder switch AS, and the controlling relays of a selector switch LW are shown.

In Fig. 2, the wipers and operating magnet D1 of switch LW, the test relay T1 of an individual line, and the hunting switch AW are shown.

In Fig. 3, the side switch of the selector switch LW is shown.

The subscriber T_n is connected to an exchange, in which connections can be set up by means of finder switches, e. g., AS, which are automatically operated on the initiation of a call and are common to a number of subscribers, and by means of selector switches e. g. LW, which are operated by number impulses. The bank contacts of the switch LW are divided into a number of groups TG, VG and RG. Subscribers of the local exchange are reached over the first group of contacts TG, while trunk lines such as VL, VL1, leading to some succeeding connecting device e. g. switch AW, are reached over the second group of contacts VG. The third group of contacts comprises contacts upon which the switch may come to rest and will remain under the influence of the calling subscriber, if it is necessary to transmit more than one train of impulses for setting up a connection

to lines in the first or second contact group. The switches AS and LW are set and the other switching operations required for establishing a connection such as testing, ringing and switching through, are effected with the assistance of an auxiliary switch known as a side switch.

The setting up of a local connection will first be described. The subscriber T_n requiring such a connection lifts his receiver, whereupon the relay A_n common to all the subscribers of the exchange operates: earth, battery, winding of the relay A_n , back contact t , lead a , subscriber's station T_n , lead b , back contact t_1 , earth. The relay A_n completes a circuit for the relay K: earth, battery, winding of the rotary magnet D¹ of the switch LW, wiper d_2 , normal contact d_4 , winding I of the relay K, side switch arm IV in position 1, front contact a_3 , earth. The rotary magnet D¹ of the switch LW does not operate in this circuit owing to the resistance of the relay K.

The relay K, however, operates and closes a circuit for the relay F: earth, battery, resistance w_4 , winding of the relay F, side switch arm III in position I, double working contact k_5 , winding II of the relay K, earth. The relay F by closing its contact f_6 connects up the side switch magnet ST: earth, battery, winding ST, front contact f_6 , earth, so that the side switch takes one step and moves into position 2. The relay F is short-circuited at the contact s_7 of the side switch magnet ST, so that it releases and causes the contact f_6 to open the circuit of the side switch magnet ST. In position 2 of the side switch, the relay interrupter RU is connected to the rotary magnet D of the switch AS: earth, battery, winding D, side switch arm III in position 2, double back contact e_8 , relay interrupter RU, earth. The switch AS thereupon rotates its wipers ka_9 , ka_{10} , ka_{11} , ka_{12} until they engage with the contacts connected to the line of the calling subscriber. Thereupon a circuit is established for the relay C: earth, battery, resistance w_{13} , front contact k_{14} , winding of the relay C, side switch arm II in position 2, wiper ka_9 , back contact t , lead a , subscriber's station T_n , lead b , back contact t_1 , earth. The relay C at its double back contact e_8 disconnects the rotary magnet D of the switch AS, and furthermore, by closing its double front contacts c_{15} and c_{16} establishes the feeding bridge: earth, battery, re-

sistance $w13$, double front contact $c15$, winding I of the relay A, back contact $u17$, wiper $ka10$, lead a , subscriber's station Tn , lead b , wiper $ka11$, back contact $u18$, winding II of the relay A, double front contact $c16$, earth. Upon the operation of the relay A which now takes place, a new holding circuit is established for the relay C, as this is directly earthed by the contact $a19$ instead of over the subscriber's line and instrument as hitherto. At the double front contact $c16$, a circuit is established for the relay T of the calling subscriber as follows: earth, battery, winding of the relay T, lead e , wiper $ka12$, double front contact $c16$, earth. Relay T operates and in known manner marks the calling subscriber's line engaged to incoming calls. Relay T also by opening its contacts t and $t1$, disconnects the relay A_n , which thereupon at its contact $an3$ opens the circuit of the relay K. The relay A at its front contact $a20$ connects earth to the relay F: earth, battery, resistance $w4$, winding of the relay F, side switch arm V in position 2, front contact $a20$, earth. The relay F connects up the side switch magnet, whereupon the side switch moves into the position 3, in which it is again disconnected by the short circuiting of the relay F. The relay V is energized in position 3: earth, battery, winding II of the relay V, bank contact $d5$, wiper $ka26$, side switch arm II in position 3, front contact $a20$, earth. Over the side switch arm I in position 3, the relay F is again energized and connects up the side switch magnet ST, whereupon the side switch moves into position 4 and is there disconnected owing to the relay F being short circuited by the contact $st7$. The relay V however remains energized in the circuit: earth, battery, winding II of the relay V, bank contact $d5$, wiper $ka26$, side switch arm II in position 4, resistance $w21$, front contact $a20$, earth.

In position 4 of the side switch, the calling subscriber transmits impulses by means of his dial for setting the switch LW on the contact of the wanted subscriber. During impulse transmission the circuit of relay A is interrupted a number of times corresponding to the number dialled: in consequence the front contact $c51$ is opened and closed a similar number of times and a circuit is established each time over the front contact $v23$ for the rotary magnet D1 of the switch LW: earth, battery, rotary magnet D1 of LW, side switch arm III in position 4, front contact $v23$, back contact $a51$, earth. The switch LW therefore rotates its wipers $ka24$, $ka25$, $ka26$ a corresponding number of steps. The circuit of the winding II of the relay V is opened as soon as the wiper $ka26$ leaves its normal contact $d5$; the relay remains energized however, over its winding I: earth, battery, resistance $w13$, double front contact $c15$, front contact $v27$, back contact $a28$, side switch arm V in posi-

tion 4, winding I of the relay V, earth. Since the relay V is made slow acting, it does not release when the back contact $a28$ is opened during impulse transmission, and thus maintains the impulsing circuit at contact $v23$ and at contact $v22$ presents the moving on of the side switch. The relay C is rendered slow acting when its winding is short circuited over the back contact $a28$ and the front contact $v27$, hence it does not release during impulse transmission. 75

If only one train of impulses is required for reaching the wanted subscriber, then, as soon as the wipers of the switch LW are set on the contacts of the wanted subscriber's line and the relay V has de-energized, the testing of the line and the ringing of the wanted subscriber take place and also the switching through of the calling and called lines after the wanted subscriber has answered. 80

If, however, more than one train of impulses is required for reaching the wanted subscriber, the wipers of the switch LW are set on one of the contacts in the contact group RG which may be called rest contacts. In this case the relay V is maintained energized in order that further impulses generated by the calling subscriber's dial may be transmitted to the rotary magnet D1 of the switch LW. The circuit for the relay V now extends as follows: earth, battery, winding II of the relay V, rest contact, e. g. rg , wiper $ka26$, side switch arm II in position 4, resistance $w21$, front contact $a20$, earth. The calling subscriber will now transmit a further train of impulses which operate as before to advance the wipers $ka24$, $ka25$ and $ka26$, so that the latter stands for instance on the contact tn . When relay V now de-energizes at the end of this train of impulses, a circuit is completed for the relay F over the back contact $v22$: earth, battery, resistance $w4$, winding of the relay F, side switch arm I in position 4, back contact $v22$, earth. The relay F operates and causes the side switch magnet ST to be connected up so that the side switch moves into the position 5, whereupon the magnet ST is again disconnected owing to the short circuiting of the relay F caused thereby. 95

In position 5 of the side switch the test relay K is connected to the lead $c1$ of the wanted subscriber's line: earth, battery, winding of relay T1, lead $c1$, subscriber's contact Tn , wiper $ka26$, side switch arm II in position 5, windings III and II of the relay K, earth. If the wanted subscriber is free, relay T1 and the relay K operate in this circuit. The energizing of the relay T1 causes the wanted subscriber's line to be disconnected in known manner from the common calling relay (not shown) and he cannot initiate a call. The testing operation is performed so quickly that the side switch mag- 100

net may be again energized at once in position 5 over its arm I and move the side switch into position 6, in which it is disconnected in known manner. The side switch is so constructed that its wipers do not leave one set of contacts until after engaging with the next, hence the movement of the side switch from position 5 to position 6 does not break the circuit over the relays K and T1. The winding III of the relay K is disconnected in the position 6 of the side switch, so that the relay K is maintained energized only by its winding II. Hence if any other selector set on this line, the corresponding relay K will be unable to energize owing to the drop of potential occasioned by the low resistance of winding II of relay K. The relay K again connects up the relay F: earth, battery, resistance w_4 , winding of the relay F, side switch arm III in position 6, double front contact k_5 , winding II of the relay K, earth, so that the side switch is moved into the position 7 in the manner previously described. The relay T1 remains energized in the following circuit: earth, winding of the relay U, side switch arm II in position 7, wiper $ka26$, contact tn , relay T1, battery, earth. The relay U however is not energized in this circuit owing to the high resistance of the winding of relay T1. The relay K releases on its circuit being opened when the side switch leaves position 6. In position 7 of the side switch, the relay F is again energized in the circuit: earth, back contact $u28$, side switch arm I in position 7, winding of relay F, resistance w_4 , battery, earth, so that the side switch moves into the position 8. In position 8 the relay T1 remains energized in the circuit: earth, front contact $a20$, side switch arm II in position 8 and over wiper $ka26$ as before. In position 8 the relay F is energized over the front contact $a20$ and side switch arm V in position 8, whereupon the side switch moves into position 9.

In position 9 of the side switch alternating current is set over the wanted subscriber's line for the first call and his bell (not shown) is rung. This circuit extends from pole changer PW, side switch arm III in position 9, wiper $ka24$ a lead of subscriber's line, subscriber's bell b , lead of his line, wiper $ka25$, side switch arm IV in position 9, to earth. When the slow interrupter LU closes its contacts, the relay F is again energized over the side switch arm I in position 9, and the side switch is thereby moved on into position 10. In this position the relay L is energized: earth, battery, relay interrupter RU1, winding of the relay L, back contact $f29$, side switch arm V in position 10, earth. The relay interrupter RU1 causes the relay L, by alternately opening and closing its front contact $l30$ at certain intervals of time (e. g. every 5 seconds) to transmit ringing current over the wanted line: earth, battery, resistance w_4 , winding of relay F, side switch arm IV in position 10, wiper $ka25$, b lead, bell of the wanted party, a lead, wiper $ka24$, side switch arm III in position 10, front contact $l30$, pole 70 changer PW. The relay F is so constructed that it does not respond to ringing current and hence does not now operate. As soon however as the wanted party takes down his receiver a direct current bridge is completed 75 across the two sides of the line by way of the transmitter (not shown) and the relay F is operated in the circuit over the called subscriber's loop and to earth at contact $l31$. The energization of the relay F effects the 80 moving on of the side switch into position 11 in the manner previously described. In position 11 of the side switch the relay L is disconnected and the speaking leads are switched through from the calling to the 85 wanted party over the side switch arms III and IV so that the transmitter of the wanted party receives feed current over the windings of the relay A. The connection has now been completely established and the conversation 90 can commence.

On the termination of the conversation both subscribers hang up their receivers. The relay A is thereby de-energized and by closing its back contact $a51$ completes a circuit 95 for the relay F as follows: back contact $a51$, back contact $v50$, side switch arm I in position 11, winding of relay F, resistance w_4 , battery, earth, so that the side switch now moves into position 1 (normal position). The release of 100 relay A also causes the relay C to release, whereupon the opening of the double front contact $c16$ causes the relay T of the calling subscriber to release. In position 1 of the side switch the relay interrupter RU is connected 105 to the rotary magnet D1 of the switch LW: earth, battery, winding of the rotary magnet D1, wiper $d2$, contact segment $d3$ side switch arm I in position 1, double back contact $e8$, relay interrupter RU, earth. The 110 switch LW thereupon rotates its wipers until its wiper $d2$ leaves the segment $d3$ and rests on its normal contact $d4$. The relay T1 of the wanted subscriber releases as soon as the front contact $a20$ opens. The switch AS 115 remains in the position to which it has been set and can now be taken into use by another calling subscriber.

The arrangement according to the invention will now be described for reaching another exchange. It will be assumed that the calling subscriber Tn desires a connection with a subscriber connected to an automatic or other exchange not shown, which is completed over the contact group VG. In that case the impulses transmitted by the calling subscriber in position 4 of the side switch cause the wipers of the switch LW to be set on a contact in the contact group VG, for instance wiper $ka26$ may be 120 125 130

set on contact $vg32$. In this case, relay V is not maintained energized and when it releases the relay F is energized over the back contact $v22$, and moves the side switch into position 5. In this position, if the line taken into use is free, relay K is energized over wiper $ka26$ contact $vg32$, back contact $t34$, resistance $w33$, battery, earth. Relay F is again connected up over side switch arm I position 5 and operates to effect the movement of the side switch to position 6, in which winding III of relay K is cut out as previously described. Furthermore, in position 6 the relay F is again energized over winding II of the relay K, double front contact $k5$, side switch arm III in position 6 and consequently the side switch moves into the position 7. In this position the relay U is energized in the following circuit: earth, battery, resistance $w33$, back contact $t34$, lead $c2$, contact $vg32$, wiper $ka26$, side switch arm II in position 7, winding of relay U, earth. The relay U opens its back contact $u28$, and thereby prevents the side switch moving on into the next position. The relay U also by opening the contacts $u17$ and $u18$ disconnects the feeding relay A. The resulting de-energization of the relay A also causes the relay C to release by the opening of contact $a19$. The relay T of the calling subscriber T_n is maintained energized over the front contact $u35$ after contact $c16$ opens. Furthermore in position 7 of the side switch, the a and b leads are switched through over the side switch arms III and IV.

When this occurs a circuit is established over the trunk line VL, VL1 for the relay S as follows: earth, battery, resistance $w36$, back contact $p37$, lead VL, wiper $ka24$, side switch arm III in position 7, wiper $ka10$, lead a , subscriber's station T_n , lead b , wiper $ka11$, side switch arm IV in position 7, wiper $ka25$, lead VL1, winding of the relay S, back contact $p38$, earth. The relay S operates and at its contact $s39$ connects the relay T2 in a circuit extending over the lead $c2$. The relay T2 operates and by opening its contact $t34$ disconnects the resistance $w33$ from the before described circuit. The relay T2 also by closing its contact $t40$ connects up the rotary magnet D2 of a non-numerical switch, e. g. AW: earth, battery, relay interrupter RU2, winding of the rotary magnet D2, back contact $p41$, front contact $t40$, earth. The switch AW rotates its wipers $ka42$, $ka43$, $ka44$, step by step and hunts for a free trunk line leading to an automatic or other exchange. When the switch finds such a line, e. g. VL2, VL3, c3, the relay P is operated in the following circuit: earth, battery, resistance $w45$, lead $c3$, wiper $ka44$, winding of the relay P, front contact $t40$, earth. The relay P by opening its back contact $p41$, disconnects the rotary magnet D2 and by closing its front contact $p46$ it short circuits one part of its

own winding, thus marking the line taken into use engaged to other subscribers. Over the line branches VL2 and VL3 the connecting up of a calling relay (manual or semi-automatic exchange) of a bridging relay (automatic exchange) located at the distant exchange is effected in known manner and by this means signalling devices or additional switches responsive to number impulses can be controlled. By closing its front contacts $p47$ and $p48$, the relay P connects the calling line through and the calling subscriber is notified in the usual manner e. g. by a buzzer signal that the line has been switched through and that he may now transmit further impulses for operating the switches in the other exchange required for completing the wanted connection. In this case the feeding current for both the called and calling lines is provided from the distant exchange.

When the calling party hangs up his receiver at the end of the conversation, the relay S is released, and this by opening its contact $s39$ opens the circuit of the relay T2. The release of the relay T2 causes the relay U in series with it also to release. When this occurs the relay F is energized over the back contact $u28$ and the side switch arm I in position 7 so that the side switch is moved on into position 8. In this position the relay interrupter RU is connected to the rotary magnet of the switch LW: earth, battery, winding of the rotary magnet D1, wiper $d2$, contact segment $d3$, side switch arm I in position 8, double back contact $c8$, relay interrupter RU, earth. The switch wipers are now rotated until the wiper $d2$ leaves the contact segment $d3$ and reaches the normal contact $d4$. When the return movement of the switch LW has been completed, the following circuit for the relay K is established: earth, battery, rotary magnet D1, wiper $d2$, normal contact $d4$, winding of the relay K, side switch arm IV in position 8, earth. The rotary magnet D1 of the switch LW cannot operate in this circuit owing to the resistance $w49$ inserted therein. The relay K however operates and by closing its double front contact $k5$ establishes the following circuit: earth, resistance $w4$, winding of the relay F, side switch arm III in position 8, double front contact $k5$, winding II of the relay K, earth. The side switch therefore moves into the position 9, whereupon the relay K releases. In position 9 of the side switch the relay F is again energized over the side switch arm I and the slow interrupter LU so that the side switch is moved into the position 10. In this position the relay F is energized over the back contacts $v50$, $a51$, and the side switch arm I, causing the side switch to move into the position 11 and thence on into the normal position 1. As already mentioned, the switch AS remains in the position in which it has been set. The opening

of the front contact $\#35$ caused the release of the relay T of the calling subscriber.

What I claim and desire to protect by Letters Patent is:—

- 5 1. In a telephone system, an automatic switch, subscribers' lines and trunk lines terminating in the banks of said switch, a set of wipers for said switch adapted to be moved in one direction only, means responsive to impulses sent to said switch for moving said wipers into engagement with the set of bank contacts corresponding to the number of impulses sent, said means including a side switch, and means for determining the extent of operation of said side switch depending on whether said wipers are positioned on the contacts terminating a subscriber's line or a trunk line.
- 10 2. In a telephone system, an automatic switch, subscribers' lines and trunk lines terminating in the banks of said switch, a set of wipers for said switch adapted to be moved in one direction only, means responsive to impulses sent to said switch for moving said wipers into engagement with the set of bank contacts corresponding to the number of impulses sent, said means including a side switch, a relay in said automatic switch for controlling the extent of operation of said side switch, and means for operating said relay in case said wipers are moved into engagement with a set of bank contacts terminating a trunk line.
- 15 3. In a telephone system, an automatic switch, subscribers' lines and trunk lines terminating in the banks of said switch, a set of wipers for said switch adapted to be moved in one direction only, means responsive to impulses sent to said switch for moving said wipers into engagement with the set of bank contacts corresponding to the number of impulses sent, said means including a side switch, means for causing the full operation of said side switch when said wipers are positioned on a set of bank contacts terminating a subscriber's line, and means for preventing the full operation of said side switch when said wipers are positioned on a set of contacts terminating a trunk line.
- 20 4. In a telephone system, an automatic switch, subscribers' lines and trunk lines terminating in the banks of said switch, a set of wipers for said switch adapted to be moved in one direction only, means responsive to impulses sent to said switch for moving said wipers into engagement with the set of bank contacts corresponding to the number of impulses sent, said means including a side

switch, means for partially operating said side switch when said wipers are positioned on a set of contacts terminating a trunk line, and means for fully operating said side switch to initiate the restoration of said switch to normal when the subscribers involved in the connection replace their receivers.

5. In a telephone system, an automatic switch, subscribers' lines and trunk lines terminating in the banks of said switch, a set of wipers for said switch adapted to be moved in one direction only, means responsive to a plurality of series of impulses sent to said switch for moving said wipers into engagement with a certain set of bank contacts depending on the number of series of impulses and the number of impulses in each series sent, said means including a side switch, and means for determining the extent of operation of said side switch depending on whether said wipers are positioned on the contacts terminating a subscriber's line or a trunk line.

6. In a telephone system, a connector, trunks and lines promiscuously interspersed in the banks of said connector, means responsive to one or more series of impulses sent to said connector for operating the connector to connect with any of said lines or any of said trunks depending on the total number of impulses sent, means operative when a line is connected with for projecting signaling current on the connected line, and means operative when a trunk is connected with for disabling said last means.

7. In a telephone system, a group of connectors, a group of subscribers' lines accessible in common to all of said connectors, a group of trunks, a different one of said trunks being accessible to each of said connectors, a non-numerical switch terminating each of said trunks, and another group of trunks accessible in common to all of said non-numerical switches.

8. In a telephone system, a group of trunks, a group of non-numerical hunting switches having their bank contacts multiply connected to said trunks, a group of subscribers' lines, and a group of connectors having certain bank contacts multiply connected to said subscribers' lines and having certain other bank contacts promiscuously interspersed with said first certain bank contacts and individually connected to separate ones of said hunting switches.

In testimony whereof I affix my signature.
ADOLF WASCHNACK.
